RAILWAY TRACK CIRCUIT APPARATUS

George R. Pflasterer, Greenville, Pa., assignor to
The Union Switch and Signal Company, Swiss-
vale, Pa., a corporation of Pennsylvania

Application May 27, 1941, Serial No. 395,402

3 Claims. (Cl. 246—112)

My invention relates to railway track circuit apparatus, and more particularly to track circuit apparatus for control of trap circuits.

At locations where a dead section occurs in otherwise continuous track circuited territory, such as multiple track railroad crossings, a trap circuit arrangement is used to continue the control established by the train approaching such crossing until the train has fully passed beyond the crossing.

Accordingly a feature of my invention is the provision of novel and improved track circuit apparatus for railway grade crossing locations.

Again, a feature of my invention is the provision of novel and inexpensive track circuit apparatus for the control of trap circuit arrangements.

The above features, as well as other objects and advantages which will become apparent as the specification progresses, I attain by arranging the railway with two track sections which extend in opposite directions from the intersection with another railway, and at least one of which sections has a single insulated joint located at a preselected point with respect to the intersection. Each section is provided with a track circuit. The track circuit for the section including the additional single insulated joint is provided with an additional series track relay that is shunted only when that portion of the section between the single insulated joint and the end of the section toward the intersection is occupied. This series track relay is used in co-operation with the other track relays of the two sections to effect a given control condition of a signaling circuit. When the two sections are separated by a dead section which is not provided with a track circuit, two additional insulated joints are used, one placed in a selected one of the rails of each of said sections at a preselected point with respect to the dead section. The track circuit for each of these two sections includes a series track relay connected around the additional insulated joint. The trap circuit is so controlled by such series track relays and the usual track relays that a predetermined control condition is effected when a train approaches the dead section and is not released until the rear of the train has passed beyond the dead section.

I shall describe one form of apparatus embodying my invention and shall then point out the novel features thereof in claims.

The accompanying drawing is a diagrammatic view showing one form of apparatus embodying my invention when used at a grade crossing.

In the drawing track circuit apparatus for a trap circuit arrangement is provided for a first one of two intersecting railroads and which apparatus permits a signal of the second railroad to be cleared when the rear of a train on the first railroad passes an additional insulated joint placed in a track section of the first railroad rather than when the train vacates the approach track section as now generally required. Such trap circuit arrangement shortens the delay to trains of the second railroad and is particularly useful when relatively long track sections are required and when relatively dense traffic exists on either or both railroads.

Looking at the drawing, a first railroad whose track rails are identified by the reference characters *1a* and *1b* is intersected at grade by a second railroad whose track is identified by the reference character *75*. The rails *1a* and *1b* are formed by insulated rail joints *2* into track sections *1T* and *2T* which are spaced apart by a dead section including the intersection of the two roads. Additional insulated rail joints *3* and *3c* are placed in rail *1b* at selected points in sections *2T* and *1T*, respectively, and each section *1T* and *2T* is provided with a track circuit, the track circuit for section *1T* including a battery *4* connected across the rails at the end adjacent the intersection, a track relay *1TR* connected across the rails at the opposite end of the section and a track relay *A1TR* connected around insulated rail joint *3c*; and the track circuit for section *2T* including a battery *6* connected across the rails at the end adjacent the intersection, a track relay *2TR* connected across the rails at the opposite end of the section and a track relay *A2TR* connected around insulated rail joint *3*.

Two signals *R2* and *L2* for the first railroad are located at the remote end of sections *1T* and *2T*, respectively, to govern traffic moving over the intersection, signal *R2* governing eastbound traffic and signal *L2* governing westbound traffic. In like manner two signals *R4* and *L4* are located along track *75* of the second railroad to govern traffic in opposite directions over the intersection. These signals may be of any standard type and are shown conventionally only. Signals *R2* and *L2* are governed through the medium of signal control relays *R2H* and *L2H*, respectively, and signals *R4* and *L4* are governed by signal control relays *R4H* and *L4H*, respectively. In the case of each such signal the operating circuits of the signal are governed over contacts of the respective control relay accord-

ing to standard practice and these signal operating circuits need not be described in detail.

The signal control relays are in turn governed by a trap circuit arrangement associated with track sections 1T and 2T and by manually operable levers SL2 and SL4, and which levers may be levers of an interlocking machine not shown. Each lever SL2 and SL4 normally occupies a center position N as indicated by solid lines in the drawing, and is movable to either a left position L or a right position R as indicated by dotted lines in the drawing. Each of the levers operates circuit controlling contacts which are shown in the usual conventional manner with each contact having placed thereon the letters N, L or R to indicate the position of the respective lever at which that contact is closed. For example, contact 85 of lever SL2 carries the letters NL to indicate that this contact is closed at both the normal and left positions of the lever.

Two directional stick relays ES and WS are included in the apparatus, relay ES being associated with eastbound traffic and relay WS with westbound traffic of the first railroad. Relay ES is normally energized over a stick circuit including contact 85 of lever SL2 and its own front contact 87, while relay WS is normally energized over a stick circuit including contact 83 of lever SL2 and its own front contact 90. A pick-up circuit for relay ES includes lever contact 85, front contact 86 of track relay 1TR and back contacts 91 and 92 of relays A2TR and 2TR, respectively; while a pick-up circuit for relay WS includes lever contact 88, front contact 89 of relay 2TR and back contacts 94 and 95 of relays A1TR and 1TR, respectively. In accordance with standard practice, a normally open contact 93 of a time element device 4TE when closed serves to shunt the back contacts 91 and 92 in the pick-up circuit of relay ES, and a normally open contact 96 of device 4TE when closed serves to shunt back contacts 94 and 95 in the pick-up circuit of relay WS.

Another stick relay 4S is provided and is controlled over a circuit which can be traced from terminal B through front contacts 97, 98, 99, 100, 101 and 102 of relays 1TR, 2TR, A2TR, A1TR, ES and WS, respectively, winding of relay 4S and to terminal C. A front contact 103 of relay 4S serves to shunt around contacts 102 and 101 of the directional relays WS and ES.

When an eastbound train is to move through section 1T and over the intersection, lever SL2 is moved to its right position R, and a control circuit for signal control relay R2H is completed from terminal B over lever contact 104, front contact 105 of relay 4S, a normally closed contact 106 of device 4TE, lever contact 107 and winding of relay R2H to terminal C, and relay R2H is picked up to close at its front contact 121 the operating circuit of signal R2 with the result that that signal is operated to a proceed position. With lever SL2 moved to its right position to open contact 85 the stick circuit for directional relay ES is opened and relay ES is released. When the eastbound train advances into section 1T, to shunt track relay 1TR opening front contact 97 interposed in the circuit for relay 4S, that relay is deenergized and released causing the circuit for relay R2H to be opened so that relay R2H is in turn released with the result that signal R2 is set at its stop position. When the head end of the eastbound train passes insulated joint 3c, relay A1TR is shunted opening front

contact 100 to open the circuit for relay 4S at a second point. Signal R2 cannot be again operated for a second train to move over the intersection until relay 4S has been reenergized, that is, until directional relay ES is reenergized and the first train has cleared sections 1T and 2T so that all the track relays are again picked up. Directional relay ES is restored to its normal condition only when lever SL2 is restored to its normal position while the train advances to the east through section 2T to shunt relays A2TR and 2TR and the rear of the train subsequently vacates section 1T permitting track relay 1TR to pick up.

However, track relay A2TR is picked up when the rear of the eastbound train on the first railroad advances over insulated rail joint 3 and hence the control circuits for relays R4H and L4H associated with the second railroad are prepared so that either of these relays can be picked up to clear the respective signals R4 and L4 by a movement of lever SL4. Assuming that as soon as the eastbound train passes beyond insulated joint 3 and relay A2TR picks up, the lever SL4 is moved to its right position R, a circuit is formed from terminal B over lever contact 110, front contacts 111, 112, 113 and 114 of relays A2TR, WS, ES and A1TR, respectively, lever contact 115, winding of relay R4H and to terminal C, and relay R4H is picked up to close at its front contact 122 an operating circuit for signal R4 with the result that signal R4 is operated to a proceed position to permit a train on track 75 to move over the intersection. In the case lever SL4 is moved to its left position L then a circuit is formed from terminal B over lever contact 116, front contacts 114, 113, 112 and 111 of relays A1TR, ES, WS and A2TR, respectively, lever contact 117, winding of relay L4H and to terminal C, and relay L4H is picked up to close at front contact 123 an operating circuit to clear signal L4 to permit a train on track 75 to move over the intersection.

Assuming the apparatus is normal and it is desired to clear signal L2 for a westbound train, the lever SL2 is moved to its left position L where a circuit is formed from terminal B, over lever contact 108, contact 108 of device 4TE, front contact 105 of relay 4S, lever contact 109, winding of relay L2H and to terminal C, and relay L2H is picked up to clear signal L2. When the westbound train enters section 2T, relay 2TR is released opening front contact 98 in the circuit for relay 4S with the result that relay 4S is released opening front contact 105 in the circuit for relay L2H and relay L2H is released to cause signal L2 to be set at its stop position. Lever SL2 when moved to its left position opens contact 88 in the circuit for directional stick relay WS and that relay is released and relay WS can be reenergized and restored to its picked up position only when lever SL2 is at its normal position N and the westbound train has moved over the intersection to enter track section 1T shunting relays 1TR and A1TR and the rear of the train subsequently vacates section 2T permitting relay 2TR to be picked up. As soon as the westbound train has cleared the intersection and the rear of the train advances beyond insulated rail joint 3c so that relay A1TR is picked up, the circuits for signal control relays R4H and L4H of the second railroad are prepared and either signal R4 or L4 can be cleared by an operation of lever SL4 to permit a train on track 75 to move over the in-

tersection. It is to be seen, therefore, that with the apparatus of the drawing, the signals R4 and L4 of the second railroad can be cleared as soon as the rear of a train on the first railroad passes either insulated joint 3 or 3c depending upon the direction of traffic and that the control established on the first railroad when a train approaches the intersection is continued until the train passes the dead section at the intersection.

Although I have herein shown and described only one form of railway track circuit apparatus embodying my invention, it is understood that various changes and modifications may be made therein within the scope of the appended claims without departing from the spirit and scope of my invention.

Having thus described my invention, what I claim is:

1. In combination, a stretch of first railway intersected at grade by a second railway and formed by insulated rail joints into two track sections one on each side of the intersection, an additional insulated rail joint placed in one rail of each of said track sections at a preselected point with respect to the intersection; a track circuit for each track section and including a current source connected across the rails at the end toward the intersection, a track relay connected across the rails at the other end and another relay connected around the additional insulated joint of the same section; signals for governing traffic in opposite directions over said intersection on said second railway, directional means controlled in part by said track relays to a first condition when said track sections are unoccupied and to a second condition when a train on said first railway approaches the intersection and which means is restored to its first condition when such train recedes from the intersection, and a control circuit governed by said directional means and by said track relays and said other relays to permit either of said signals to be cleared when a train approaching the intersection on said first railway has passed over the intersection and the rear of the train has passed beyond the additional insulated joint of the track section through which the train is receding from the intersection.

2. In combination, an east-west railway intersected by a north-south railway and formed by insulated rail joints with an east and a west track section which are separated by a dead section including the intersection, an additional insulated rail joint placed in one rail of each of said track sections at a point preselected with respect to the dead section; a track circuit for each of said track sections and including a current source connected across the rails at the section end adjacent said dead section, a first track relay con-

nected across the rails at the section end remote from the dead section and a second track relay connected to said one rail around the additional joint of the respective section; said first and second track relays of each track circuit normally energized and picked up, an eastbound and a westbound directional relay, each of said directional relays normally energized through a stick circuit including a normally closed contact of a signal governing device and which contact is opened when a train is to approach the intersection on said east-west railway in the direction corresponding to that of the directional relay, a pick-up circuit for each directional relay including a front contact of the first track relay for the track circuit of the corresponding section and a back contact of the first track relay for the track circuit of the opposing section, a signal for the north-south railway to govern traffic over the intersection, and a control circuit including a front contact of each of said directional relays and a front contact of each of said second track relays for governing said signal.

3. In combination, an east-west railway intersected by a north-south railway and formed by insulated rail joints into two track sections separated by a dead section which includes the intersection, an additional insulated rail joint placed in one rail of each of said track sections at a point preselected with respect to the dead section; a track circuit for each of said track sections and including a current source connected across the rails at the section end adjacent said dead section, a first track relay connected across the rails at the section end remote from said dead section and a second track relay connected to said one rail around the additional joint of the same section; said first and second track relays of each track circuit normally energized and picked up, an eastbound and a westbound signal to govern traffic through said track sections, a manually operable means for controlling said signals, an eastbound and a westbound directional relay; circuit means for each of said directional relays and including contacts of the manually operable means and of each of said first track relays to normally energize that directional relay, to deenergize that relay when the manually operable means is set to clear the associated signal for a train to approach the intersection and to reenergize that relay when such train recedes from the intersection; a signal for the north-south railway to govern traffic over the intersection, and a control circuit including a front contact of each of said directional relays and a front contact of each of said second track relays for governing the last mentioned signal.

GEORGE R. PFLASTERER.
